UNITED STATES PATENT OFFICE

GUSTAV O. BRANDT, OF DETROIT, MICHIGAN, ASSIGNOR TO L. A. YOUNG SPRING & WIRE CORPORATION, OF DETROIT, MICHIGAN

CLIP-APPLYING TOOL

Application filed May 17, 1928. Serial No. 278,575.

The main object of this invention is to provide a plier-like tool for use in applying connecting clips for parts of spring structures, the tool being particularly designed 5 for the joining of a coiled spring tie member to a connected part.

A further object is to provide a tool of the class described for applying clips, which is adapted to simultaneously offset one of the 10 members united, thereby preventing longitudinal movement of such offset member relative to the clip.

Objects pertaining to details and economies of my invention will definitely appear 15 from the description to follow. The invention is defined in the claims.

A structure which is a preferred embodiment of my invention is clearly illustrated in the accompanying drawing forming a part 20 of this application, in which:

Fig. 1 is a perspective view of my improved tool.

Fig. 2 is a detail view partially in longitudinal section on line 2—2 of Fig. 4.

25 Fig. 3 is a detail view corresponding to that of Fig. 2 with the tool closed.

Fig. 4 is a detail view partially in transverse section on line 4—4 of Fig. 3.

Fig. 5 is a fragmentary plan view of a 30 spring structure for the assembly of which the tool illustrated is well adapted.

In the embodiment illustrated in the drawing my improved tool comprises a pair of jaw members 1 and 2 connected by a pivot 3 and 35 provided with handles 4. A spring 5 is connected to the handles and acts to normally open the tool.

The jaw members are provided with jaws 6 and 7 having outwardly curved faces 8 and 40 9 respectively. The jaw 7 is provided with stepped shoulders 10 at the ends of its face disposed in planes at the outside of the planes of the sides of the jaw 6.

The faces 11 of the jaw members between 45 their jaws are forwardly curved, these curves being complementary and merging into the curvature of the faces of the jaws with the reverse curves.

The work illustrated consists of coiled 50 springs. The clips 12 illustrated are formed

of wire and are in the form of a loop having the bight portion thereof folded upon itself and lying in spaced relation to the arms of the loop. The arms terminate in forwardly curved bills so that the clips may be placed 55 in the jaws as shown in Fig. 2.

The parts to be connected in the embodiment illustrated consist of helically coiled body springs 13 and the coiled spring tie members 14. These parts are arranged in 60 relation to the clips as shown in Fig. 2 and the tool is closed, clamping the clip upon the parts to be connected and at the same time offsetting the portion 15 of the tie member embraced by the clip as is clearly shown in Figs. 65 4 and 5.

As the jaws are closed the shoulders 10 engage the coils of the tie members which lie adjacent to the coils embraced by the clip so that such coils are securely held by the closing of the jaws thereon. 70

This offsetting of the parts engaged by the clip provides shoulders or stops so that longitudinal movement of the member 14 within the clip in either direction is prevented. 75

While I have especially designed the tool for the application of clips in spring structures such as shown in Fig. 5, it is desirable for use in applying other forms of clips; that is, the clip may be a sheet metal stamping with the same result from the offsetting. 80 Further, the tool may be adapted for applying clips to and offsetting tie members other than coiled spring tie members.

I have not attempted to illustrate or describe such modifications as it is believed in the disclosure made will enable those skilled in the art to embody or adapt my invention as may be desired.

Having thus described my invention what 90 I claim as new and desire to secure by Letters Patent is:

1. A tool of the class described comprising a pair of pivotally connected jaw members 95 provided with handles and with jaws having opposed outwardly curved faces, one of the jaws having forwardly projecting stepped shoulders disposed in planes at the outside of the planes of the sides of the other jaw, said jaw members having complementary for- 100

wardly curved work supporting faces between the jaws merging into the curvature of the jaws with the reverse curves.

2. A tool of the class described comprising a pair of pivotally connected jaw members provided with handles and with jaws having opposed outwardly curved faces, one of the jaws having forwardly projecting shoulders disposed at the ends of and in planes transverse to its curved face and at the outside of the planes of the sides of the other jaw.

3. A tool of the class described comprising a pair of coacting jaw members provided with jaws having opposed outwardly curved faces, one of the jaws having forwardly projecting shoulders disposed in planes at the outside of the planes of the sides of the other jaw, said jaw members having complementary forwardly curved work supporting faces between the jaws merging into the curvature of the jaws with the reverse curves.

4. A tool of the class described comprising a pair of coacting jaw members provided with jaws having opposed outwardly curved faces, one of the jaws having forwardly projecting shoulders disposed at the ends of and in planes transverse to its curved face and at the outside of the planes of the sides of the other jaw.

5. A tool of the class described comprising a pair of coacting jaw members provided with jaws having opposed outwardly curved faces; one of the jaws having forwardly projecting shoulders at the sides of its face, said jaw members having complementary forwardly curved work supporting faces between the jaws merging into the curvature of the jaws with the reverse curves.

6. A tool of the class described comprising a pair of coacting jaw members provided with jaws having opposed outwardly curved faces, one of the jaws having forwardly projecting shoulders at the ends of its face and in planes transverse to its face.

45 In witness whereof I have hereunto set my hand.

GUSTAV O. BRANDT.
